UNITED STATES PATENT OFFICE.

WILLIAM H. PLATT, JR., OF BROOKLYN, NEW YORK.

COLLAPSIBLE CRATE.

SPECIFICATION forming part of Letters Patent No. 579,805, dated March 30, 1897.

Application filed May 29, 1896. Serial No. 593,659. (No model.)

To all whom it may concern:

Be it known that I, WILLIAM H. PLATT, Jr., a citizen of the United States, residing at Brooklyn, in the county of Kings and State 5 of New York, have invented certain new and useful Improvements in Folding or Collapsible Crates, of which the following is a specification.

My invention relates to a new and useful 10 improvement in folding or collapsible crates, and has for its object to provide a device of this description which may be folded into a small compass for convenience in shipping, and when desired for use may be quickly ad- 15 justed, so as to be as firm and serviceable as a crate of ordinary construction.

A further object of my invention is to re- 20 duce the cost of such crates, so that they may come into general use, thus displacing the ordinary crates, which after reaching their destination and being emptied become an ob- struction.

With these ends in view my invention con- 25 sists in the details of construction and com- bination of elements hereinafter set forth, and then specifically designated by the claim.

In order that those skilled in the art to 30 which this invention appertains may understand how to make and use the same, I will describe its construction and operation in de- tail, referring to the accompanying drawings, forming a part of this specification, in which—

Figure 1 is a central longitudinal section of a crate made in accordance with my im- 35 provement, illustrating its appearance when adjusted for use; Fig. 2, a cross-section of the same; Fig. 3, a cross-section of the several parts of the crate when folded into position for transportation, and Fig. 4 a perspec- 40 tive of the crate when ready for shipment.

In carrying out my invention I hinge the bottom A and two sides B and C together by the hinges D and E, so that the lower edge of the side B will swing over the upper sur- 45 face of the bottom A and the lower edge of the side C will swing back upon said surface, as clearly shown in Fig. 2. The ends F are hinged at G to the side C, so that when swung in the position shown in Fig. 1 they may be 50 secured to the side B by the hasps H, which are adapted to engage the staples I, so that by the passage of a cotter-pin J through each

of the staples the hasp will be prevented from disengagement from said staples, thereby holding the ends in their proper relation to 55 the remainder of the crate. When the bottom, sides, and ends have been thus secured, the top L, which is hinged at K to the side B, may be swung into position, so as to close the crate and there secured by the hasp M in 60 conjunction with the staple N, through which the hasp of a padlock O may pass. The edge of the top next the hinges K is beveled, and a corresponding bevel formed upon the upper edge of the side B permits the top to swing 65 open without obstruction, as will be readily understood.

From this description it will be seen that a crate built in accordance with my improve- 70 ment may be collapsed by the withdrawal of 75 the cotter-pins and the disengagement of the hasps H from their staples, when the top, two sides, and bottom may be folded into the po- sition shown in Fig. 3, the ends F folding backward onto the side C, and when this has 75 been accomplished it is obvious that the crate may be secured against displacement by the passing of a cord therearound or otherwise, and when so folded the crate may be shipped to any distance without the liability of in- 80 jury, and, as is well understood, this is of great advantage in devices of this descrip- 85 tion, in that after goods have been shipped in such a crate and the latter has been emptied it may be again returned to the place of ship- 90 ment for reuse, thus obviating the necessity of supplying a new crate after their shipment of goods.

When the crate is to be used for eggs or similar articles requiring the division thereof 90 into compartments, this I accomplish by pro- 95 viding a partition P, which may be fitted into suitable grooves formed in the sides of the crate, so that when the crate is collapsed these partitions may be removed and placed upon the side C in the space intervening between the two ends F, as clearly shown in Fig. 4.

One of the principal advantages of my im- 100 provement is that when adjusted for use it will be as rigid as though made in the ordi- nary way, and yet the cost to produce such a crate is but little in excess of that now required to produce the ordinary crate.

Slight modifications might be made in the

construction here shown without departing from the spirit of my invention, and I therefore do not wish to be limited to the exact design described.

5 Having thus fully described my invention, what I claim as new and useful is—

The collapsible crate consisting of the bottom, the sides and the top all hinged together and the transverse partition with its ends set 10 into said sides the hinges connecting said top and one side and the hinges connecting said bottom and the opposite side being on the

inside and arranged at diagonally opposite points and the hinges connecting the aforesaid side and bottom being on the outside and 15 diagonally opposite the hasp or entrance to the crate, substantially as shown and described.

In testimony whereof I have hereunto affixed my signature in the presence of two subscribing witnesses.

WILLIAM H. PLATT, JR.
